UNITED STATES PATENT OFFICE.

HARRY D. HAMMOND, JOHN W. ACHELPOHL, AND ABNER LESLIE, OF ARGONIA, KANSAS.

COLLAPSIBLE CRATE.

1,425,587.

Specification of Letters Patent. Patented Aug. 15, 1922.

Application filed August 16, 1921. Serial No. 492,710.

To all whom it may concern:

Be it known that we, HARRY D. HAMMOND, JOHN W. ACHELPOHL, and ABNER LESLIE, all citizens of the United States, and all 5 residing at Argonia, in the county of Sumner and State of Kansas, have invented certain new and useful Improvements in Collapsible Crates, of which the following is a specification.

10 This invention relates to improvements in collapsible crates made of metal and designed particularly for the transportation of poultry, although suitable for other commodities.

15 The object of the invention is the provision of a metal crate which is sufficiently strong to withstand the rough usage to which it will be subjected under operating conditions, but which will be of comparatively light weight and easy to assemble.

20 A further object of the invention is the provision of a crate of this character which may be readily expanded for the purpose of adapting it to be filled with the commodities 25 to be transported, and which may be as easily contracted, or "knocked-down," so as to occupy a much reduced space, for return to its original source.

25 A still further object of the invention is 30 the provision of a crate as above described, equipped with adjustably mounted wires or rods adapted to prevent egress from the crate of the poultry or other commodities retained therein. Other objects, incident to 35 those recited, will be pointed out in the following specification.

In the accompanying drawings,

Figure 1 is a perspective view of the crate expanded.

40 Fig. 2 is a central section of the crate in folded or knock-down position.

Fig. 3 is a top plan view of the crate.

Fig. 4 is a central section of the crate in expanded position.

45 Fig. 5 is an end view of the crate.

Fig. 6 is a cross section taken on line 6—6 of Fig. 4.

50 Fig. 7 is a detail of a telescoping member adapted to retain the crate in its expanded or contracted position.

Fig. 8 is a detail of a vertical side brace used on the crate, and

Fig. 9 is a sectional detail showing means of adjustment of the retaining wires or rods.

55 Referring specifically to the drawings,

which show an embodiment of our invention, Fig. 1 shows a crate provided, on each side, with upper rails 1 and lower rails 2, and upon each end with upper rails 3 and lower rails 4. Vertical braces 5 are provided 60 for each side of the crate, one at each end and one at approximately the middle thereof, and horizontal braces 6 extend across the top of the crate, at each end and near the middle.

65 As shown in Fig. 1, the side braces 5 are provided with flanges 7 extending at right angles to the body portion of the braces 5. The said flanges 7, carried by the braces 5 which are located at the ends of the crate, 70 therefore form end braces for the crate, and serve as a support for the retaining wires or rods, as hereinafter explained. The flanges on the middle braces 5 extend into the interior of the crate, and the purpose thereof 75 will be hereinafter discussed.

The side rails 1, are provided with inwardly turned flanges 8, and the bottom rails 2 are similarly provided with flanges 9. A floor 10 rests upon and is riveted or otherwise secured to said flanges 9.

80 In the assembly of the crate as so far described, the rails 1 and 2 are pivotally secured, at *a* to the respective ends of the braces 5, and the rails 3 and 4 are riveted or 85 otherwise rigidly secured to the flanges 7 of the end side braces 5. The braces 6 are rigidly secured to the inwardly turned flanges 8 of the rails 1, and a rectangularly shaped skeleton structure is thereby formed, adapted 90 for pivotal movement upon *a*.

95 The retaining wires or rods 11 are provided to prevent egress from the crate of the poultry or other commodities therein contained. Each wire is a continuous member, provided with a hook at each end. A plurality of apertures are provided in the end flanges 7, and, extending through each of said apertures, is an internally screw threaded sleeve 12, provided with a head 13, having therein a recess 14 for the reception of a screw driver or other operating tool. Short stub wires or rods 15, having externally screw threaded shanks adapted to extend into and operatively engage the threads 100 within the sleeve 12, are provided for each of the wires 11 used upon the sides of the crate. The outer ends of the wires 15 are provided with hooks adapted for connection with the hooks upon the ends of the wires 110

11. The construction just described is shown in Figs. 2, 4 and 9. The wires 11 are thread-ed through apertures in the middle flanges 7, which act as guides and preserve the 5 parallel relation of said wires 11. The hooks 16 on the stub wires 15, are then engaged with the hooks on the ends of the wires 11; the sleeves 12 are then inserted through the 10 apertures in the end flanges 7, and the free 15 ends of the stub wires 15 introduced into the sleeves 12. A rotation of the sleeve 12, through the proper manipulation of a suitable tool inserted in the slot 14, will exert a pull to tighten the wires 11, as will be ob- 20 vious, and it is equally clear that the wires 11 may thus be adjusted to any desired ten-sion.

The top wires 11 are hooked at each end, and extend between the braces 6 on the top 25 of the crate, the hooks entering apertures provided in said braces as clearly shown in the drawings. Similarly, the end wires 11 extend between the end flanges 7, as clearly shown.

25 In order to furnish a door for the crate, we provide a slid-able panel 17, extending across the top thereof. Said panel 17 ex-tends over and upon a strip 18, connected to the lower surface of the flanges 8, as shown 30 in Fig. 1, the panel also extending under the braces 6, at each end and the middle. Inserts 19 are provided on each side of the ends and at the middle of the panel 17, said inserts being secured in position by fasten- 35 ing members extending through the braces 6 and the strip 18. This construction pro-vides a track or guide for the panel, said guide being formed between the adjacent edges of the inserts 19, and the bottom of 40 brace 6 and the top of strip 18. As a means of preventing undesired longitudinal move-ment of the panel 17, I provide a pin 20, se-cured to a chain 21, and adapted for inser-tion through an aperture in the middle brace 45 6, through a registering aperture in the panel 17, and also through a third register-ing aperture in the central strip 18. The chain 21 is connected to a ring which encir-cles one of the wires 11.

50 In the construction shown in Fig. 1, when the crate is pressed downwardly to the position shown in Fig. 2, the bottom of the crate remains stationary, and the top moves to the right, the rails 1 pivoting on the upper ends 55 of the end braces 5, which latter pivot at their lower ends on the stationary rails 2. In order to permit the necessary pivotal move-ment of the braces 5 however, the upper left-hand corner thereof is rounded off, 60 and the lower right-hand corner is similarly rounded off, as shown in Fig. 8. During the pivotal movement hereinbefore described, the curved lower edges of the braces 5, rock on the floor 10 of the crate, while the curved 65 upper edges rock upon the lower surface of

the flanges 8. Because of the sharp corner 5^a, at the top of the braces 5, pivotal move-ment to the left, beyond the position shown in Fig. 1, is effectively resisted.

We provide upon each side of the crate, 70 means for retaining the crate in expanded or contracted position, such means consist-ing of a sheath 22, pivoted at its bottom to the lower end of the left hand brace 5. Said sheath is adapted for the reception of a bar 75 23, which extends therein, the outer end of said bar being pivoted at a to the upper end of the middle brace 5. This construction is clearly shown in Figs. 1 and 7. The sheath 22 is perforated at 24 for the reception of a 80 pin 25, connected to a chain 26 secured to the crate. An aperture 27 is also provided in the bar 23, at such a position that, when the crate is in the position shown in Fig. 1, the aperture in the sheath and in the bar, 85 will register and the pin 25 may be inserted through both apertures and lock the crate in that position. The lower portion of the bar 23 is also provided with another aper-ture, so positioned as to register with the 90 aperture in the sheath 22, when the crate is contracted, as shown in Fig. 2, in which po-sition the pin 25 may be inserted and lock the crate in that position.

It is to be noted that, in the position 95 shown in Fig. 1, the upper rail 3, at the left end, is dropped below the brace 6, while the lower rail 4 is immediately adjacent the floor. Conversely, at the right end of the crate, the upper rail 3 is immediately adja- 100 cent the brace 6, and the lower rail 4 is raised from the floor 10. This construction prevents interference with the pivotal move-ment of the crate, as will be understood.

It is to be noted that wires 11 extend be-tween the flanges 7, carried by the middle braces 5, thereby forming a partition ex-tending substantially centrally of the crate, and dividing the latter in sections. The ad-vantages of sectional crates are obvious. 110

The operation of our crate is believed to have been sufficiently described in the fore-going and no further elaboration is nec-essary.

The rails, floor and braces are preferably 115 of sheet metal, as are also the sheath 22, and the bar 23, providing a structure which is entirely of metal, but which might be pro-duced, to operate, of other material, at a sacrifice of durability.

It is obvious that those skilled in the art may vary the details of our construction and the arrangement of parts without de-parting from the spirit of our invention, and therefore we do not wish to be limited to 125 such details except as may be required by in-terpretation of the appended claims.

We claim:

1. In combination with a collapsible crate provided with a bottom and with a top and 130

- sides adapted for pivotal movement thereon to a contracted or expanded position, of a member pivoted to said sides and adapted for the reception of another member pivoted 5 to said sides, and means for locking said members together to hold the crate in either its expanded or contracted position.
2. A crate provided with top and bottom members mounted for relative swinging 10 movement, whereby the crate may be expanded or contracted, and with means for locking said crate in either position, said means comprising co-acting locking elements pivotedly carried by said members, one of 15 said elements being reciprocably mounted within the other and means for preventing relative reciprocation of said elements when the crate is in expanded or contracted position.
- 20 3. A crate provided with a bottom and a top supported to swing thereon whereby the crate may be expanded or contracted, an apertured sheath pivoted to the bottom of said crate, a bar pivoted to the top of the 25 crate and extending into said sheath, said bar being provided with two spaced apertures, and means adapted to extend through the aperture in said sheath and one of the 30 apertures in said bar, to lock said crate in expanded position, or to extend through the
- aperture in said sheath and through the other aperture in said bar to lock the crate in its contracted position, substantially as described.
4. A crate provided with a top and bottom, corner members pivotally connected adjacent their ends to said top and bottom, a plurality of sleeves extending through said corner members, a stub member extending through each of said sleeves and in screw-threaded engagement therewith, and a closure member for said crate, connected to said stub member and secured to the opposite corner member, substantially as described. 35 40 45
5. A crate provided with a top and bottom, corner members pivotally connected adjacent their ends to said top and bottom, a plurality of sleeves extending through said corner members, a stub member extending through each of said sleeves and in screw-threaded engagement therewith, and means in the outer end of said sleeve, whereby rotation thereof, to vary the position of said stub member therein, is facilitated. 50 55

In testimony whereof we affix our signatures.

HARRY D. HAMMOND.
